UNITED STATES PATENT OFFICE.

GOTTLOB HONOLD, OF STUTTGART, GERMANY, ASSIGNOR TO THE FIRM OF ROBERT BOSCH, OF STUTTGART, GERMANY.

MECHANICAL INTERRUPTER FOR ELECTRIC IGNITION SYSTEMS.

1,070,893.

Specification of Letters Patent. Patented Aug. 19, 1913.

Application filed April 9, 1912. Serial No. 689,548.

To all whom it may concern:

Be it known that I, GOTTLÖB HONOLD, a subject of the Emperor of Germany, and residing at Stuttgart, Germany, have invented 5 certain new and useful Improvements in Mechanical Interrupters for Electric Ignition Systems; and I do hereby declare the following to be a full, clear, and exact description of the invention, such as will enable others skilled in the art to which it app- 10 pertains to make and use the same.

The present invention relates to mechanical interrupters for electric ignition systems for internal combustion engines, and partic- 15 ularly to an interrupter of simple and effective organization having one of its coöperative interrupter contacts mounted upon a de- formable carrier which is periodically de- 20 formed in such manner as to separate the contacts.

It has heretofore been the practice, in the construction of mechanical interrupters to mount the movable contact terminal upon the free end of a blade spring or upon the 25 free end of a pivoted lever pressed by a spring toward the circuit-closing position; and to arrange suitable cams or projections in such manner as to periodically engage and shift the blade spring or lever to sepa- 30 rate the contact terminals. This arrange- 35 ment has the disadvantage that the free contact-carrying end may be strongly influenced in its movements at high speeds by individual oscillations of the spring or lever, where- by the exact determination of the periods of ignition may be seriously interfered with.

In the invention herein disclosed, an in- 40 terrupter contact mounted intermediate the ends of a deformable carrier, having both ends steadied against vibration, is moved relatively to the coöperative contact by an actuating cam acting directly upon the car- 45 rier against spring pressure, whereby the disturbing vibrations are avoided and a slight movement of one or both of the ends of the carrier effects a comparatively wide and quick break. Preferably the deform- 50 able carrier comprises an arched spring fastened at one end to the rotatable member of the interrupter and having its other end attached to a movable block which is peri- 55 odically moved toward the fixed end of the carrier by an actuating cam, thereby moving the interrupter contact mounted on the 60 carrier intermediate of the ends thereof

away from the coöperative contact mounted on the rotatable member. In this way, the movable contact may be mounted so as to be free from the undesirable oscillatory effects, even at high rotative speeds, while the construction is simple and the operation thor- 60oughly reliable.

In the accompanying drawings, illustrating preferred forms of my invention, Figure 1 is a plan view, and Fig. 2 is a longitudinal 65 section thereof on line 2-2 of Fig. 1; Fig. 3 is a plan view, and Fig. 4 is a side view of a modification within the invention.

In Figs. 1 and 2, the interrupter disk *a* is mounted in the ordinary way upon the end 70 of the shaft of an electric ignition machine *r*, for example, and has a lug *g* on one side and radial guides *h* *h* on the opposite side. The deformable carrier comprises the ax- 75 ially arched spring *c* and the fiber block *f*. The spring *c* is attached at one end to the rotatable member *a* by the pin *e*, and at the other end to the block *f* by the pin *e'*, these pins preferably lying in planes parallel to the plane of rotation and allowing the 80 spring to move slightly there around during the period of deformation. The block *f* is arranged to slide radially between the guides *h* and to project into the path of the actuating cam and is prevented from axial 85 movement by the spring pressed plate *i* as shown. An interrupter contact *b* is carried by the rotatable member *a* within the plug *k* of insulating material, and is preferably 90 made adjustable in the usual way. The co- 95 operative interrupter contact *d* is carried by the arched spring *g* intermediate the ends thereof, and is normally held by the spring in proper engagement with *b* to effect good electrical contact at all times, even at high 100 rotative speeds. One or more actuating cams *m* are arranged within the housing *n* in the path of rotation of the projecting end of the block *f*. The housing *n* may be angu- 105 larly adjusted by means of the lever *p* to adjust the period of ignition in the well-known manner. When the interrupter disk *a* is rotated, the block *f* of the carrier peri- 110 odically engages the actuating cams *m* and is directly moved inwardly toward the end of the spring fastened at *e*. In this period of actuation the spring *c* is deformed against its pressure and the relatively movable in- 115 terrupter contact *d* is moved axially away from the coöperative contact *b* to interrupt

the electric circuit at this point with a quick and comparatively wide break.

The construction shown in Figs. 3 and 4 is similar to that previously described with the exception that the spring *c* is arched in a radial direction instead of in an axial direction, and the pins *e* *e*¹ are set axially, while the plug *k* of Figs. 1 and 2 carrying the contact *b* is replaced by the plug *l* fastened to and insulated from the interrupter disk *a*. Furthermore, the guide *h* in Figs. 3 and 4 completely surrounds the block *f* so that the spring-pressed plate *i* of the previous construction is not required in this case. The method of operation of this embodiment of my invention will be readily apparent from above.

Although I have shown normally stationary actuating cams (*i. e.*, cams which are stationary except during adjustment) and rotatable interrupter parts, it will be readily understood that this arrangement may be reversed if desired. So also, the action consequent upon the engagement of the cam and the deformable carrier may be utilized to bring the interrupter contacts together instead of separating them, and they may be separated or brought together by simultaneous engagement with actuating cams on both ends.

Having thus described my invention, what I claim is:

1. In a rotatable mechanical interrupter for electric ignition systems, a pair of co-operative interrupter contacts, a deformable carrier steadied at both ends against vibration and carrying one of said contacts, and an actuating cam having a radially actuating surface adapted to deform said carrier radially upon engagement therewith and thereby separate said contacts.

2. In a rotatable mechanical interrupter for electric ignition systems, a pair of axially disposed co-operative interrupter contacts, a deformable carrier steadied at both ends against vibration and carrying one of said contacts, and an actuating cam having a radially actuating surface adapted to deform said carrier radially upon engagement therewith and thereby separate said contacts in an axial direction.

3. In a mechanical interrupter for electric ignition systems, a pair of co-operative interrupter contacts, a deformable carrier carrying between its ends one of said contacts, and a cam adapted to move the ends of the carrier more nearly together upon engagement therewith and thereby separate said contacts with a quick and comparatively wide break. 60

4. In a mechanical interrupter for electric ignition systems, a pair of co-operative interrupter contacts, a rotatable member carrying one of said contacts, a deformable carrier attached at one end to said member and carrying between its ends the other of said contacts, a normally stationary cam adapted to deform said carrier upon engagement with the other end thereof and thereby separate said contacts with a quick and comparatively wide break. 70

5. In a rotatable mechanical interrupter for electric ignition systems, a pair of co-operative interrupter contacts, an arched spring steadied at both ends against vibration and carrying between its ends one of said contacts, and an actuating cam having a radially actuating surface adapted to bring the ends of the spring more nearly together and thereby separate said contacts with a quick and comparatively wide break. 75

6. In a mechanical interrupter for electric ignition systems, an interrupter disk, an arched spring attached at one end to said disk, an interrupter contact mounted on said disk, an axially disposed co-operative interrupter contact mounted on said spring intermediate the ends thereof, a radially movable block fastened to the other end of said spring, guides on said member for said block, and an actuating cam projecting within the path of said block to engage it and bring the ends of said spring more nearly together and thereby separate said contacts with a quick and comparatively wide break. 90

In testimony whereof I affix my signature, in presence of two witnesses.

GOTTLOB HONOLD.
